DESIGN.

M. R. LOUDON.

CARPET.

No. 17,778.

Patented Oct. 11, 1887.

UNITED STATES PATENT OFFICE.

MILTON R. LOUDON, OF JERSEY CITY, NEW JERSEY, ASSIGNOR TO THE
BIGELOW CARPET COMPANY, OF CLINTON, MASSACHUSETTS.

DESIGN FOR A CARPET.

SPECIFICATION forming part of Design No. 17,778, dated October 11, 1887.

Application filed September 13, 1887. Serial No. 249,501. Term of patent 3½ years.

To all whom it may concern:

Be it known that I, MILTON R. LOUDON, of Jersey City, county of Hudson, and State of New Jersey, have invented a new and original 5 Design for Carpets, of which the following is a specification, reference being had to the accompanying photograph, which forms a part of the same.

The invention relates to a design to be worked 10 into or upon surfaces, such as carpets or similar fabrics; and it consists in the novel configuration and grouping of figures herein specifically shown and claimed.

The accompanying photograph is a face view 15 of a carpet showing my new design.

My design comprises a body part, A, and a border, B.

The body A of my design consists of an assemblage, in a close continuous mass, of circular flower forms and prominent veined leaves 20 projecting here and there from underneath the flower forms. Most of the flowers are large and clearly distinguished, the leaves of the flowers being generally broad and rounded. 25 Here and there appear long narrow tapering leaves.

My border B has a narrow inner margin, on which is a row of small conventional ornaments. Next to this margin is a bed of circular flower forms and leaves. These flowers 30

and leaves are assembled in separate groups, each of which has one large circular flower at the center, around which the smaller leaves and flowers are clustered. The rest of the border is divided into sections corresponding 35 to and placed just above these separate groups by means of line-work. Each of these sections has a small center ornamented with dotted work encircled by a row of small star-shaped flowers. Along the sides of these sections are 40 rows of larger star-shaped flowers and leaves. At the top are several long narrow diverging leaves. In the angles formed between the bounding-lines of the successive sections are heart shaped ornaments. The outer part of 45 the border is ornamented with parallel line-work and dotted work, with other conventional ornaments.

What I claim as new, and desire to secure by Letters Patent, is—

1. In a design for carpets, the body A, substantially as shown.
2. In a design for carpets, the border B, substantially as shown.
3. The design for carpets, consisting of the body A and border B, substantially as shown.

MILTON R. LOUDON.
